US0D1055069S

(12) **United States Design Patent** (10) **Patent No.:** **US D1,055,069 S**
Nicholas et al. (45) **Date of Patent:** **** Dec. 24, 2024**

(54) **PROTECTIVE COVER FOR A LAPTOP COMPUTER**

(71) Applicant: **MAX Interactive, Inc.**, Irvine, CA (US)

(72) Inventors: **Sean Nicholas**, San Clemente, CA (US); **Albert George Giazzon**, Mesa, AZ (US)

(73) Assignee: **Max Interactive Inc.**, Irvine, CA (US)

(**) Term: **15 Years**

(21) Appl. No.: **29/838,387**

(22) Filed: **May 12, 2022**

(51) **LOC (14) Cl.** **14-02**

(52) **U.S. Cl.**

USPC **D14/440**

(57) **CLAIM**

The ornamental design for a protective cover for a laptop computer as shown and described.

DESCRIPTION

FIG. 1 is a perspective view of a protective cover for a laptop computer, showing my new design;

FIG. 2 is a second perspective view thereof;

FIG. 3 is a front elevational view thereof;

FIG. 4 is a rear elevational view thereof;

FIG. 5 is a left side elevational view thereof

FIG. 6 is a right side elevational view thereof;

FIG. 7 is a top plan view thereof; and,

FIG. 8 is a bottom plan view thereof.

Broken lines illustrate portions of the protective cover for a computer laptop that form no part of the claimed design.

1 Claim, 6 Drawing Sheets
